UNITED STATES PATENT OFFICE

2,041,961

EXPANSION JOINT AND CORE

Robert R. Robertson, Chicago, Ill., assignor to
 The Translode Joint Company, Chicago, Ill.,
 a corporation of Illinois

Application July 18, 1934, Serial No. 735,730

22 Claims. (Cl. 94—18)

This invention relates to concrete road expansion joints and particularly to an improved core unit retainable in position between concrete road sections, said core unit being constructed of a substantially compressible and elastic material having the upper portion thereof shaped to permit the core unit to be anchored in opposite concrete sections and furthermore shaped to afford a support for a removable filler mold and cap and for a plastic filling when the mold and cap are removed after the pouring of concrete.

It is an object of this invention to provide a road expansion joint forming mechanism including in combination a core unit constructed of a compressible and flexible material, said core unit being retainable in the road construction between adjacent concrete sections by anchoring members formed on the sides of the core unit, and embedded in opposite sections of the road.

It is also an object of this invention to provide an expansion joint forming mechanism including a load transmission base unit having supported thereon a compressible and flexible core unit having anchoring means integrally formed on the sides thereof to be embedded in opposite concrete sections of a road and furthermore having the upper portion of the core unit formed for the removable support of a filler void forming mold and cap which are replaceable after the pouring of the concrete by a filling or plastic material to partially close the expansion joint void formed above the core unit.

It is a further object of this invention to provide a road expansion joint mechanism including a load transmission base having a core of plastic material supported thereon and retainable in the road structure between adjacent road sections by means of anchoring bars or ribs formed on the core on opposite sides of a core groove whereby the core unit is anchored in adjacent concrete sections of the road permitting the upper grooved portion of the core unit to be opened and closed with the contraction and expansion of the road sections due to temperature changes.

It is furthermore an object of this invention to provide an expansion joint forming mechanism including in combination a load transmission base including means for rapidly transmitting loads between adjacent road sections and having a core supported thereon, said core being constructed of rubber or the like and having anchoring bars or members integrally formed on the sides of the upper portion thereof on opposite sides of a top groove adapted to receive a filling of a plastic material for partially closing the void formed be-

tween concrete road sections above the core unit after the pouring of concrete and after the removal of a mold member and cap which are removably supported on the core unit prior to the pouring of concrete.

Another object of the invention is to provide a road expansion joint forming mechanism including a core unit which is supported in reversed staggered load transmission anchor shoes the base flanges of which are provided with longitudinally disposed ribs or beads formed on the top surfaces thereof to wedgingly coat with arched ribs formed on the top portions of a base member for the purpose of more rapidly transmitting loads from one concrete section to an adjacent road section.

It is an important object of this invention to provide a road expansion joint forming mechanism having a rubber or flexible core unit provided with integral anchoring wings or members to be embedded in opposite concrete sections of a road, and also being provided with a top groove for the reception of a plastic filler for partially closing the space between adjacent concrete sections of a road and above the core unit.

Other and further important objects of this invention will be apparent from the disclosures in the specification and the accompanying drawing.

The invention (in a preferred form) is illustrated in the drawing and hereinafter more fully described.

On the drawing:

Figure 1 is a transverse vertical fragmentary section taken through an expansion joint forming mechanism and a concrete road, and illustrating an improved flexible core unit embodying one of the essential features of this invention.

Figure 2 is an enlarged fragmentary detail section through the upper portion of the road expansion joint after the joint cap has been removed but showing the filler mold still in position to permit proper edging of the upper adjacent edges of the concrete road sections.

Figure 3 is a detailed fragmentary sectional view similar to that illustrated in Figure 2 with the filler mold removed and replaced by a plastic filler for filling the core groove and a portion of the crack or void formed between the road sections above the core unit.

Figure 4 is a fragmentary side elevation of the upper corner portion of the flexible core unit illustrating the positioning of the filler mold and cap.

Figure 5 is a fragmentary transverse section

through a modified form of an expansion joint the anchor shoes of which are provided with projecting means for causing a wedging action with arched portions of the base member for the rapid 5 transmission of loads between adjacent road sections.

As shown on the drawing:

Figure 1 illustrates an improved road expansion joint forming mechanism including an improved load transmission base which is supported 10 on a road subgrade. Formed upon the road subgrade is the upper or crown section of the road comprising adjacently positioned concrete road sections 1 separated by the expansion joint 15 mechanism.

The improved load transmission expansion joint mechanism includes a load transmission base unit which serves as a load transmitting mechanism between the adjacent sections of a 20 concrete road, and in the present showing comprises an elongated base member consisting of a solid base plate 2 constructed of sheet metal or other suitable material. The longitudinal margins of the base plate 2 are bent upwardly and 25 then inwardly toward one another to form oppositely positioned guide channels 3. The guide channels 3 of the base unit provide oppositely positioned guide grooves 4. The margins of the top plates of the guide channels 3 are bent upwardly and are cut away to provide spaced upwardly projecting retaining flanges or fingers 5. The retaining flanges 5 on opposite sides of the base unit are staggered with respect to one another. Notches are provided between the retaining 30 flanges 5 on each side of the base unit to permit load transmitting anchor shoes or holders to be seated therein in proper spaced relation for the support of a core unit hereinafter more fully described. The load transmitting mechanism 35 associated with the base unit consist of a plurality of anchor shoes or holder sections which are movably or shiftably engaged in the base section and are arranged longitudinally in offset or staggered relation with respect to one another. The anchor shoes or holders are of substantially 40 identical construction and are arranged with the adjacent shoes reversed with respect to one another as clearly illustrated in Figure 1. Each of the anchor shoes is constructed of metal and 45 comprises an angle bar including a base flange 6 and an upright flange or web 7 integral with said base flange. Struck outwardly from the upper margin of each of the anchor shoe upright flanges or webs 7 are anchoring blades or wings 8 leaving 50 the inner side of the upright flange or web flat. Supported on the base flanges 6 of the anchor 55 shoes between the upright flanges or webs 7 is a solid core unit constructed of solid rubber or a synthetic rubber composition or similar material and comprising a body or slab 9, the top surface or edge of which is provided with a V-shaped longitudinal groove 10 extending throughout the entire length of the core unit. Formed on each 60 side of the core unit near the upper edge thereof is an anchoring bar or rib 11 of dovetailed cross-section or the like to permit the anchoring bars to be securely embedded in the concrete forming 65 the road sections 1. As clearly illustrated in Figures 2 and 3, the anchoring bars 11 are positioned opposite one another substantially at the level of the lower portion of the core groove 10.

Seated upon the top of the rubber or plastic core 9 is an edging mold of substantially T-shaped cross-section comprising a top bar or block 12 70 and an integral downwardly projecting shank or

web flange 13 which is tapered complementally to the shape of the core groove 10 to permit the mold web 13 to seat within said groove 10 as clearly illustrated in Figure 1. Removably engaged over the filler mold 12-13 and over the upper portion of the core 9 is a channel cross-sectioned mold cap 14 the side flanges of which are positioned adjacent the sides of the upper portion of the core body 9 and seat on the anchor bars 11 to complete the expansion joint forming 10 mechanism.

With the joint forming mechanism in position as illustrated in Figure 1, concrete is poured on opposite sides of the joint forming mechanism to form the road sections 1. After the concrete on opposite sides of the road forming mechanism has set sufficiently, the joint cap 14 is removed from between the road sections. With the aid of proper edging tools the concrete on opposite sides of the void, resulting from the removal of the cap, is rounded as clearly illustrated in Figure 2 with the aid of the edging mold 12. After the edging of the concrete on opposite sides of the void, the mold 12 is also removed and a filling of plastic material is deposited to fill the core groove 25 10 and a portion of the crack or void above the core to form the wedge filler 15.

With the contraction and expansion of the road sections 1 on opposite sides of the expansion joint, the anchor shoes forming part of the base 30 unit are permitted to move transversely of the base unit for the purpose of transmitting loads from one section of the road to an adjacent section. With the contraction and expansion of the road sections due to temperature changes, the 35 flexible core 9 is acted on by the concrete sections and since the upper portion of the core unit is anchored to the road sections by means of the anchor bars 11 the upper mouth shaped portion of the core is adapted to be opened and closed 40 with the contraction and expansion of the road sections. With the opening and closing movement of the mouth portion of the rubber core, the plastic filler 15 is permitted to adjust itself in 45 the crack or opening formed between the road sections above the core unit.

Figure 5 illustrates an expansion joint mechanism including a modified form of base unit adapted to be supported on a road subgrade to be 50 embedded between concrete road sections 1 for supporting a core unit 9 in position. The modified form of base unit is a rapid load transmission device which will almost immediately start the transmission of loads from one road section to an adjacent section. The modified base unit 55 comprises a metal base plate 16 having the longitudinal margins bent upwardly and inwardly to form guide channels 17 forming guide grooves or pockets 18. Each of the top flanges or plates 19 of the base is formed with an integral longitudinally disposed arched rib 20 which extends 60 throughout the entire length of the base.

Load transmitting anchor shoes are arranged in reversed staggered relation in the base. Each anchor shoe comprises an upright flange 21 having anchoring blades or wings struck outwardly therefrom, similar to the blades or wings 8 illustrated in Figure 1. Integrally formed at substantially right angles on the upright flange 21 is a base flange 22 the top surface of which is arched 70 to form a longitudinally disposed bead or rib 23. The beads 23 are positioned to wedgingly seat or engage in the arched ribs 20 of the base top flanges 19.

Stresses and strains resulting from the expansion 75

sion and contraction of the road sections due to temperature changes are also rapidly transmitted from one road section to an adjacent section through the medium of the anchor wings with the assistance of the interfitting rib members 20 and 23. The rib members 20 and 23, due to the inclined frictionally engaged surfaces thereof act to increase the rapidity with which loads are transmitted between adjacent road sections of a road or other concrete construction.

It will of course be understood that various details of construction may be varied through a wide range without departing from the principles of this invention, and it is therefore, not the purpose to limit the patent granted hereon otherwise than necessitated by the scope of the appended claims.

I claim as my invention:

1. An expansion joint forming device comprising a load transmission base, a solid core of flexible material supported on the base and having dovetail shaped anchoring means formed thereon for anchoring the core to adjacent sections of a concrete construction, and void forming means removably supported on the anchoring means and removable from the concrete to leave a void for the reception of a filler.

2. An expansion joint forming mechanism comprising a load transmission base, a core of compressible material supported on the base, said core having anchoring means formed thereon for anchoring the core in adjacent concrete sections of a concrete construction, a mold member removably supported on the core, and a cap removably engaged on the core for enclosing the mold member during the pouring of concrete and removable to permit edging of the concrete with the assistance of the mold member.

3. An expansion joint forming mechanism comprising a load transmission base, a core of compressible material supported thereon and having a pair of oppositely positioned anchoring means formed on the sides thereof for anchoring the core in adjacent sections of a concrete construction, filler void forming means removably supported on the anchoring means and removable after the pouring of concrete to leave a filler void above the core, and a removable edging mold in the void interfitting the core.

4. An expansion joint forming mechanism comprising a base, load transmission members shiftably supported on the base, a core of compressible material supported between the load transmission members, anchoring means on the core, and filler void forming members interfitting one another and removably supported on the anchoring means.

5. An expansion joint forming mechanism comprising a base, a plurality of load transmission members shiftably supported on the base, a core of compressible material supported between the load transmission members, anchoring means formed on said core for anchoring the core to adjacent sections of a concrete construction, and closure means covering the core and supported on the anchoring means.

6. An expansion joint forming mechanism comprising a base means, a plurality of load transmission members transversely shiftable with respect to the base means and with respect to one another, a grooved core of compressible material supported between the load transmission members, anchoring means integrally formed on the compressible core for anchoring the core to adja-

cent sections of a concrete construction, and a plastic filler above the core and projecting downwardly to fill the core groove.

7. An expansion joint forming mechanism comprising a base means, load transmission members shiftably supported in the base means, a core of elastic material supported between the load transmission members, anchoring means formed on the core for anchoring the core to adjacent sections of a concrete construction, said core having a groove therein, a mold member supported on the core and projecting downwardly into the core groove, and a cap engaged over the mold member and over the upper portion of the core.

8. An expansion joint forming mechanism comprising a load transmission base, and a split core of plastic material supported thereon and including dovetail cross-sectioned anchoring means formed on the core for anchoring the core in adjacent sections of a concrete construction and for opening and closing the split core with the contraction and expansion of the sections due to temperature changes.

9. An expansion joint forming mechanism comprising a base, a core of plastic material supported on the base and having anchoring means formed on the sides of the core for anchoring the core to adjacent sections of a concrete construction, said core having a groove formed in the top thereof, and a plastic filler supported on the core between the concrete sections and extending downwardly to fill the core groove.

10. An expansion joint forming mechanism including in combination a core having a filler receiving mouth portion, said core comprising a solid body of plastic material having a pair of oppositely positioned plastic anchoring means of dovetailed cross-section formed on the sides of the mouth portion for anchoring the core in adjacent sections of a concrete construction.

11. An expansion joint forming mechanism including in combination a core unit comprising a plastic body having a filler receiving groove formed in the upper portion thereof, and also having dovetailed anchoring means projecting from the sides of the grooved portion of the body for anchoring the body in adjacent concrete sections of a concrete construction.

12. An expansion joint core unit comprising a body of rubber composition material having a wedge shaped filler receiving groove formed in the top thereof and having anchoring members integrally formed on the sides thereof on opposite sides of said groove.

13. An expansion joint core unit comprising a solid body of rubber-like material having the upper portion thereof grooved to form an adjustable mouth portion for the reception of a plastic filler, said core body having anchoring means integrally formed on the sides of the mouth portion thereof.

14. A road expansion joint mechanism including in combination a base including anchoring means for anchoring the base to adjacent sections of a concrete construction, and a core of plastic material having an adjustable mouth and supported on the base and having a pair of oppositely positioned tapered anchoring means for anchoring the core in the adjacent concrete sections of the concrete construction to open and close the adjustable mouth with the contraction and expansion of the road sections.

15. An expansion joint forming mechanism comprising a load transmission base, a core of

- solid plastic material supported on the base and having a mouth-like upper portion, and means projecting from the sides of the mouth-like upper portion of the core for connecting the same with adjacent sections of a concrete construction to cause opening and closing of the mouth portion of the core with the contraction and expansion of the concrete sections due to temperature changes.
16. An expansion joint forming mechanism comprising a base, a recessed core supported thereon, and dovetail bars on the recessed portion of the core for interlocking the same with adjacent concrete sections of a concrete construction to cause opening and closing of the recessed portion of the core with the contraction and the expansion of the concrete sections due to temperature changes.
17. An expansion joint forming mechanism including in combination a core constructed of a plastic material having a grooved mouth-like upper portion with anchoring means formed on opposite sides thereof for anchoring the core in adjacent sections of a concrete construction and for opening and closing the mouth-like portion of the core with the contraction and expansion of the sections due to temperature changes.
18. An expansion joint core unit comprising a solid plastic body having a groove formed in the upper end thereof, and plastic anchoring means projecting from the sides of the upper grooved portion of said body.
19. An expansion joint core unit comprising an elastic body having a wedge shaped groove therein, and elastic anchoring means integrally formed on the sides of said body, said anchoring means diverging outwardly from the sides of the plastic body in the form of dovetail bars.
20. An expansion joint core unit comprising a plastic body having a mouth portion and means for opening and closing the same.
21. An expansion joint core unit including a solid preformed rubber like plate, and rubber like anchor bars integrally formed on opposite sides of the plate near the upper edges thereof, said bars diverging outwardly from the sides of the plate to provide grooves above and below the bars for the reception of concrete.
22. An expansion joint core unit comprising a solid precast rubber like plate having oppositely disposed dovetail cross-sectioned bars integrally formed on the sides thereof and extending from end to end of said plate, said bars providing grooves for the reception of concrete to interlock the core with concrete slabs cast on opposite side of the core.

ROBERT R. ROBERTSON.
